(57) CLAIM

The ornamental design for a waistband for pants, as shown and described.

DESCRIPTION

FIG. 1 is a front perspective view of a waistband for pants showing my new design;

FIG. 2 is an enlarged front view thereof; and,

FIG. 3 is an enlarged rear view thereof.

The broken lines shown in FIGS. 1-3 depict environmental subject matter only and form no part of the claimed design.

1 Claim, 3 Drawing Sheets

FIG. 3
